POCKET FISHING GAME DEVICE

Jean Frechmann, Paris, France

Application March 25, 1949, Serial No. 83,479

2 Claims. (Cl. 273—1)

1

The present invention relates to a toy or game device.

It is an object of the present invention to provide a novel toy or game device which will be of great interest and of high amusement and entertainment value to its users.

It is another object of the present invention to provide a game device which requires and, therefore, develops manual skill and dexterity in the players or users of the game.

It is also an object of the present invention to provide a game of the character described which may be used with equal interest and amusement value by a single, individual player or competitively, by two or more players.

It is still another object of the present invention to provide a game device of the character described which is of relatively simple concept and may be readily understood and played even by younger children.

It is a further object of the present invention to provide a game device of the character described which is small and compact, occupies but little space, and may be conveniently and comfortably carried in a pocket, purse or the like, for use at any time and place desired.

It is a still further object of the present invention to provide a game device of the character described which is of simple, sturdy and economical construction, which is attractive in appearance, and which is simple and easy to manipulate.

The foregoing and other advantages and superiorities of the game device of the present invention, which may be generally described as a "pocket fishing game," will become more readily apparent to those skilled in the art from the embodiment thereof shown in the accompanying drawings and from the description following. It is to be understood, however, that such embodiment is shown by way of illustration only, to make the principles and practice of the invention more readily comprehensible, and without any intent of limiting the invention to the specific details therein shown.

In the drawings:

Fig. 1 is a view in front elevation of a game device of the present invention; the portions in broken lines indicating an alternate position of its manipulable portions;

Fig. 2 is a vertical section taken on line 2—2 of Fig. 1; and

Fig. 3 is an enlarged fragmentary exploded view of a floating game piece and of the movable magnetic attractor therefore; the former being shown in section to illustrate its construction.

2

Referring more specifically to the accompanying drawings, the game device of the present invention comprises a completely enclosed "fishing pond" comprising a hollow, completely closed housing, generally designated as 10, which may be formed of a flat back wall 11, and an arcuate or trough shaped front section 12, joined in water-tight manner to the back wall 11, to form a completely water-tight receptacle.

10 The wall 11 and the front 12 may preferably be formed of a relatively rigid synthetic plastic material many suitable ones of which are well known in the trade, and the front section may preferably be transparent. The housing may be 15 made oval shaped, as shown, for comfort in carrying in a pocket, or it may have a flat bottom, enabling its convenient positioning on a supporting surface.

10 The housing 10 is partly filled with water 13 20 to about half its height, in which water there may be disposed a plurality of floating elements 14, each of which may have secured thereto a piece of ferrous, magnetically attracted metal, such as iron, and designated as 15. The elements 15 14 may preferably be formed of hollow, hermetically sealed plastic containing sufficient air or displacement to support itself and the attached metallic head 15 in floating position in the water, and it may, preferably, be formed in the shape 25 of a marine animal, such as a fish, as illustrated.

30 Formed in the upper portion of the back wall 11, at a distance above the water level, is a relatively small aperture 16 through which is inserted a thin, rigid rod 17 projecting partly into the 35 receptacle 10 and partly to the exterior thereof. The inner end of the rod 17 has a fishing line 18 tied thereto, to the end of which, in turn, is tied or otherwise secured a magnet 19. The outer end of the rod 17 is enclosed on a flexible, closed 40 ended sleeve 20, the flared edges of which 21 are cemented or otherwise secured in air-tight and water-tight manner to the wall 11, to hermetically seal the receptacle or housing 10.

45 It will be apparent that by flexing the sleeve 20 from side to side and up and down the magnet 19 may be moved about to contact the ferrous heads 15 of the several elements 14 to attach them to itself and to then bring one or more of them at a time out of the water, thus "catching" and "landing" the fish. The game may be 50 considered as having for its object to catch and land all of the fish simultaneously.

To facilitate the manipulation of the rod 17 while the game device is being held in the hand 55 facing the player, a finger piece 30 may be provided on the upper side of the sleeve 20.

In order to make the game competitive, either for an individual player or for a set of players, a time element may be introduced during which the game is to be completed. Thus, timing means may be incorporated into the game device in the form of a sand glass 25. The sand or hour glass 25 may be supported on a bracket 26, secured to or integrally formed with the upper end of the side wall 11 of the housing 10. The glass 25 may have a band 27 around its waist portion, which band may be formed with apertures 28 in which the tapered ends 29 of the bracket 26 may be inserted to pivotally support the sand glass 25 for ready inversion. By these means a single player can conveniently compete against time or a number of players may compete against one another, on a time basis, as to which may complete the fishing in the least elapsed time.

To give the game a realistic touch, there may be placed on the inner face of the back wall 11, above the water line, the figure of a fisherman and appropriate scenery surrounding him, with the figure so disposed that the rod 17 appears to be held in normal and natural fishing position relative to the figure of the fisherman.

This completes the description of the game device of the present invention and the manner of its use. It will be readily apparent that many modifications and variations thereof may be made by any one skilled in the art, in accordance with the principles of the invention hereinabove set forth and without the use of any inventive ingenuity. I desire, therefore, to be protected for any and all such modifications and variations that may be made in the game device of the present invention within the spirit of the invention and the scope of the claims hereto appended.

What I claim is:

1. A game device of the character described, comprising a wholly closed water tight housing partly filled with water, a plurality of floating elements each having a fragment of ferrous metal secured thereto disposed within the said water, said housing having an aperture formed therein above the level of said water, a rod partly inserted into the said housing through said aperture, said rod having a magnet suspended from its inner end, a flexible sleeve fitted over the said rod exteriorly of said housing, said sleeve closed at one end and its other end hermetically secured to said housing around said aperture.
- 15 2. The game device of claim 1 wherein said floating elements are of hollow pneumatic, hermetically sealed construction.

JEAN FRECHTMANN.
